UNITED STATES PATENT OFFICE.

ALGOT LEVIN CHRISTENSON, OF STOCKHOLM, SWEDEN.

BOX-BEARING.

No. 905,845.

Specification of Letters Patent.

Patented Dec. 8, 1908.

Application filed April 29, 1907. Serial No. 370,851.

To all whom it may concern:

Be it known that I, ALGOT LEVIN CHRISTENSON, a subject of the King of Sweden, and resident of Stockholm, in the Kingdom 5 of Sweden, have invented new and useful Improvements in Box-Bearings, of which the following is a specification, reference being had to the drawing accompanying and forming a part hereof.

10 Several different constructions have more or less successfully been tried in order to yieldingly support axle-bearings in centrifugal machines. At first, one or more spiral springs were placed in the bearing, said 15 spring or springs being wound around the same, or the spiral spring itself formed the bearing, in which case it was wound from a flat wire. Also spiral springs extending radially in relation to the bearing and several 20 other constructions comprising springs have been used, but either they have been expensive in manufacturing and difficult to repair, when the springs break, or they have not served their purpose inasmuch as 25 they have been more or less insensitive and generally not durable.

The object of this invention is to provide a box-bearing for centrifugal machines, in which the form of the spring insures sensitivity in combination with great durability.

30 The invention consists, chiefly, in that the spring placed between the axle-box and the inside of the spring casing forms a folded band bearing alternately on the box and on the outer casing in such a manner that one 35 of two branches of each part of the spring lying between two adjacent points of contact of the spring with the casing extends in a direction substantially tangential to the 40 box, while the other branch connecting two subsequent tangential parts forms an acute angle with the former one. The branch of the spring connecting the tangential part with the subsequent one may, suitably, 45 bear on the latter so as to be yieldingly supported thereby. By this means a very gentle yielding is obtained which is uniform in all directions round about the box.

In the drawing, Figure 1 is a horizontal 50 section of a box bearing embodying the invention. Fig. 2 is a similar view of a somewhat modified construction.

Referring to Fig. 1, the spring is made in one piece and bent in such a manner that one

of the two parts *a* and *b* forming together a 55 wave or fold has such a position in relation to the box as to be bent or caused to yield sideways, when the box moves laterally, and at the same time glide against the box. The other part, which is suitably S-shaped, extends, 60 on the contrary, in a substantially radial direction and is exposed to compression between the box and the outer casing. The part *a*, thus swings about the fixed fulcrum *c*, while the part *b* is compressed, and 65 at the same time a gliding motion takes place between the part *a* and the box *d*, and such a gliding and yielding motion also takes place between the other parts *a* of the spring and the box. 70

The spring illustrated in Fig. 2 is bent in substantially the same manner as that shown in Fig. 1. The only difference is that the inner portion of each of the parts *b* is in contact with and bears on the adjacent part *a*. 75 This form of construction is far more advantageous than that shown in Fig. 1 as the spring, as a whole, will be more expansive, due to the fact that the two parts *a* and *b* bearing on each other are, thereby, made to 80 better coöperate with each other.

Having now described my invention, what I claim as new and desire to secure by Letters Patent is:

1. In a box-bearing, the combination of an 85 axle-box, a casing surrounding the said box, at a distance therefrom, and a spring in the shape of a ribbon placed on edge between the casing and the box and folded so as to bear alternately on the box and on the outer casing in such a manner that one of the two 90 branches of each part of the spring lying between two adjacent points of contact of the spring with the casing extends in a direction substantially tangential to the box, while the other branch connecting two subsequent tangential parts forms an acute angle with the former, substantially as and for the purpose set forth.

2. In a box bearing, the combination of an 100 axle-box, a casing surrounding the said box, at a distance therefrom, and a spring placed between the casing and the box and forming a folded band bearing alternately on the box and on the outer casing in such a manner 105 that one of the two branches of each part of the spring lying between two adjacent points of contact of the spring with the casing ex-

tends in a direction substantially tangential to the box, while the other branch connecting two subsequent tangential branches forms an acute angle with the former and bears on the subsequent tangential part, substantially as and for the purpose set forth.

In testimony whereof I have signed my

name to this specification in the presence of two subscribing witnesses.

ALGOT LEVIN CHRISTENSON.
